SHUTTLELESS LOOM

Theodor Vorck, London, England, assignor to
United Elastics Limited, London, EnglandApplication August 30, 1939, Serial No. 292,697
In Great Britain September 19, 1938

3 Claims. (Cl. 139—123)

This invention relates to shuttleless looms of the kind wherein a thread laying member other than a shuttle is passed to and fro through the warp shed to lay loops of weft threads therein.

5 The invention also includes shuttleless looms or machines provided with a selvedge forming device such as are used in the manufacture of ribbons, tapes, braids and like narrow webs of fabric.

10 The chief object of the invention is to provide an improved weft laying device and in selvedge looms or machines to ensure that a uniform selvedge is formed on the fabric.

15 Another object of the invention is to provide a shuttleless loom with a weft thread laying member slidably mounted at one end on a driving member having a component of motion across the shed. A further object is to provide a weft thread laying member which is constrained to move against a cam or guide surface or is guided in a slot whereby on operation of the driving member the free end of the thread laying member carrying the weft thread is moved to and fro through the shed in a predetermined curved path to lay the weft thread in the shed.

20 A further object of the invention is to provide a shuttleless loom with means for forming a selvedge at the side of the fabric. Another object is to provide a knitting needle and arrange for it to be operated to engage and interknit the weft loops as they are laid in the shed to form a selvedge. A final object is to provide a fixed thread guide pin for assisting in directing the thread into engagement with the needle.

25 To enable the invention to be fully understood it will now be described by reference to the accompanying drawing in which:

30 Fig. 1 is a plan view of a unit for use in shuttleless looms for producing narrow webs of fabric having a knitted selvedge in accordance with the invention and

35 Fig. 2 is a side elevation thereof looking in the direction of the arrow Fig. 1.

40 Fig. 3 is a diagrammatic plan view of the warp and weft threads drawn to a larger scale and showing the formation of the knitted selvedge.

45 As shown the weft laying member and the co-operating knitting needle are arranged as a unit on a breast block 1 adapted to be secured to the loom frame 2 as by screws 3. The warp threads 4 are passed through heddles operated to form a shed in any usual manner and it is thought to be unnecessary to illustrate the shed forming mechanism. The weft thread 5 is laid through

50 the shed by a weft laying member 6 having an

eye 7 for the thread. The web thus woven passes under a bar 8 and between adjustable guides 8a mounted on a plate 8b to the usual take-up roll (not shown).

5 For operating the weft laying member 6, a bar 9 is slidably mounted in the loom frame and adapted to be reciprocated across the frame by any suitable means, a slide 11 being secured at right angles to the bar with a plate 12 having a curved slot 13 therein fixed to the frame 2 above the slide. A pin 14 carrying an arm 15 to which the thread laying member 6 is rigidly attached passes through the slot 13 and is secured to a cross head 16 moving in the slide 11. Thus on reciprocation of the bar 9 the pin 14 is slidably guided to and fro in the slot 13 thereby moving the member 6 to and fro through the shed in a curved path 6a. The angle of the slide 11 relative to the bar 9 and the shape of the slot 13 may be varied in any suitable manner provided that the eye 7 of the weft laying member 6 is slidably moved in a curved path to and fro through the shed and travels beyond the extremity of the shed so that in its extreme position it is over the selvedge knitting needle and can co-operate therewith.

20 To form a knitted selvedge by knitting the weft loops one into the other a latch knitting needle 17 carried in a holder 18 is provided, the holder being reciprocated by an eccentric 19 driven from the driving shaft 20 of the loom as shown. A pin or thread guide 21 is fixed to a bracket 22 on the breast block 1 parallel to and in the horizontal plane of the needle 17, its free end being bent upwardly to rise above the latch of the needle (Fig. 2). The pin 21 is preferably made of 25 spring steel.

30 In forming the selvedge the needle 17 is moved forward as the weft loops are laid by the weft laying member 6 and the thread guide 21 meets the weft thread of each loop and ensures that it is guided into the needle hook. As the weft laying member 6 moves out of the shed the needle 17 recedes carrying the last laid weft loop with it and draws it through a loop formed by the last preceding pair of weft threads laid during the last preceding pick of the loom as indicated in Fig. 3. Thus a selvedge of interknitted weft threads is formed. This method of forming the knitted selvedge is already known and further 35 description thereof is thought to be unnecessary. While the knitting needle used is preferably of the latch type, a bearded needle, or needle of any suitable type may be used as will be understood. If desired the thread guide pin 21 may 40

45

50

55

be dispensed with and a needle having a guide combined therewith as described in the specification of co-pending application for Letters Patent of the United States of America Ser. No. 292,698 filed Aug. 30, 1939, substituted therefor.

Further a separate selvedge thread may be drawn from a bobbin or the like and knitted into the weft loops in known manner if desired. The selvedge forming mechanism may be employed at one or both sides of the loom. In the latter case two thread laying members such as 6 will be provided one on each side of the shed. A comb may be provided on the loom frame to assist in beating up the weft threads. The curved path in which the weft laying member 6 moves however enables the weft to be laid tightly in the fell and thus serves to beat up the wefts but a reed or sley may also be employed.

The thread laying member 6 may be of any suitable shape and its length and angular position relative to the member 15 may be adjusted by a suitable sliding and/or pivotal connection maintained by a clamping screw or the like as indicated at 23 Fig. 1.

25 The pin 14 is shown as moving in the curved slot 13 but it will be understood that a cam may be substituted for the slot and the pin 14 suitably pressed against the cam as by a spring for example. Further it will be understood that a loom may be fitted with a series of weft laying members of the kind hereinbefore described, with or without a series of selvedge forming mechanisms, adapted to operate simultaneously on a series of sheds to produce a series of fabric strips.

35 The mechanism shown is readily adapted to be applied to a loom as a complete unit.

I claim:

1. In a shuttleless loom and in combination, a driving member, means for imparting to the driving member a component of motion across the

shed, a thread laying member slidably mounted at one end on the driving member, a curved guide surface, and means for urging the thread laying member against the curved guide surface, so that on operation of the driving member the free end of the thread laying member carrying the weft thread is moved to and fro through the shed in a predetermined curved path to lay the weft thread in the shed. 5

2. In a shuttleless loom and in combination a loom frame, a transverse bar, means for reciprocating the bar in the loom frame, a guide secured to said bar at an angle thereto, a plate having an arcuate slot therein fixed to said frame, a cross head slidably mounted in said guide, a pin fixed to said cross head and passing through said slot and carrying a thread laying member, the arrangement being such that when the bar is reciprocated the pin is constrained to move to and fro along said slot whereby the thread laying member is moved in an arcuate path to and fro through a shed of warp threads to lay loops of weft threads therein. 10

3. In a shuttleless loom and in combination a loom frame, a transverse bar in the loom frame, 25 means for reciprocating the bar transversely in the frame, a slide fixed at an angle to said bar, a cross head, means for moving the cross head in the slide, a curved slot in a plate fixed to the frame, a pin fixed at its lower end to said cross 30 head and passing through said slot and weft laying member fixed at one end to the upper end of said pin, the arrangement being such that when said means is operated to reciprocate the bar in the frame the cross head moves in the slide and the pin is moved to and fro along the slot and thus imparts to the weft laying member a movement to and fro across the shed in a predetermined curved path. 35
